AUTOMATIC VOLUME CONTROL FOR TELEPHONE RECORDING APPARATUSES

Lincoln Thompson, Cheshire, Conn., assignor to
The SoundScriber Corporation, New Haven,
Conn., a corporation of Connecticut

Application November 21, 1942, Serial No. 466,455

5 Claims. (Cl 179—6)

This invention relates to electrical phonograph recorders, and more particularly to an automatic volume control system for recording conferences and two-way conversations in a telephone line.

One object of the present invention is to provide an automatic volume control unit and apparatus of the above nature designed to be connected to the terminals of a telephone receiver in such a manner that the installation will in no way affect or impair the telephone transmission or absorb any appreciable amount of current energy from the telephone circuits, thus avoiding any possible service problems.

Another object is to provide an automatic volume control apparatus of the above nature designed to be inserted between the telephone line or other circuit and the input of the amplifier of a phonograph recorder.

A further object is to provide an apparatus of the above nature in which the high intensity of the local voice currents is cut down or "attenuated" so as to reduce the contrast with the weaker distant voice currents and thus permit "clearer" recording.

A further object is to provide an apparatus of the above nature housed in a suitable casing and including a "shunting" copper oxide rectifier, a "biasing" copper oxide rectifier, a volume control knob, and a selector switch to permit selective recording from a microphone or from the telephone line.

A further object is to provide a simple attachment of the above nature which may be connected to an individual recording unit on the user's desk to provide this automatic volume control feature as an external addition to the recording apparatus without need for connection to a power line or to batteries.

A further object is to provide an automatic volume control apparatus and system of the above nature which will be simple in construction, inexpensive to manufacture, easy to install and connect at both ends of the telephone line, easy to manipulate, compact, and very convenient, efficient, and durable in use.

With these and other objects in view there have been illustrated on the accompanying drawings several forms in which the invention may be conveniently embodied in practice.

In the drawings:

Figure 1 represents a plan view of the phonograph recording cabinet, the volume control casing, and the various electrical plugs and connector cords employed therewith.

Figure 2 is a circuit diagram of the same.

Figure 3 is a circuit diagram of a modified form of the invention employing a pair of shunting rectifiers in push-pull relationship.

Figure 4 is a circuit diagram of another modi-

fied form of hookup also embodying the invention and in which a "preamplifier" is employed.

The present invention is designed to couple an ordinary telephone line with a standard type of phonograph recorder, such as disclosed in the Patent No. 2,250,242 to Lincoln Thompson, dated July 22, 1941, and entitled "Disk dictating machine."

The purpose of the present invention is to permit the faithful recording of a two-way telephone conversation or other source of signals in which weak signals from a distant telephone or other weak source are combined with stronger signals from a nearby transmitter or from another strong source.

This is accomplished by providing an improved automatic volume control unit which will substantially balance the effects of the distant and local voices of the telephone conversation.

In addition to the above function of balancing the loud and soft voices, the present system also reduces the level of the signals from the entire telephone line which is too high for use with the recording apparatus mentioned above, so that a much lower signal level will be impressed upon the input of said apparatus. In addition, it reduces the volume of the high level signals much more than it does the volume of the low level signals on the line.

Theory of operation

The improved automatic volume control apparatus of the present invention depends for its operation upon the shunting effect of a copper oxide rectifier across a part of the signal input circuit, which is so arranged that a variation in the shunting impedance at the point of application of said rectifier will produce a substantial change in the signal voltage applied to the input of the recorder amplifier.

In actual use, the telephone line will be connected to a transformer primary through a pair of condensers and a pair of resistances, and the secondary of said transformer is included in a circuit having a copper oxide rectifier in shunt therewith.

When the copper oxide shunt rectifier provides a load on the secondary of the transformer it reflects back to the primary of the transformer and introduces a voltage drop by virtue of the transformer losses and the resistances and condensers connected in series with the telephone line.

The variation of the shunting impedance of this rectifier is produced by varying the D. C. biasing voltages applied through a second copper oxide rectifier which rectifies a portion of the output signals from the recorder amplifier. These rectified signals are smoothed by a condenser-resistance network and appear as direct

current biasing voltage in series with the shunting copper oxide rectifier. A strong telephone signal will produce a strong D.C. biasing voltage and thereby cause the shunting rectifier to produce a large amount of shunting effect. A weak telephone signal on the other hand will produce very little D.C. biasing voltage, and the shunting effect of the first copper oxide rectifier will therefore be very low for such signals.

Thus, for weak signals, the shunting copper oxide rectifier will produce only a small reduction in the signals entering the recorder amplifier, and for strong signals it will produce a decided reduction.

Description

Referring now to the drawings in which like reference numerals denote corresponding parts throughout the several views, the numeral 10 indicates a phonograph recorder of the type disclosed in the Thompson Patent No. 2,250,242 mentioned above, designed for recording dictation and other sounds on a rotating disk record 11. The recorder cabinet is provided with a control knob 12 for adjusting the gain of the amplifier (not shown) employed in connection therewith. The record is driven by a motor (not shown) under the control of a lever switch 12a, said motor being energized by a power cord 13 having a two-prong plug 14 for connection with any convenient electric power socket.

The amplifier of the recorder 10 is adapted to be connected with the "L₁" and "L₂" terminals (not shown) of a standard telephone apparatus by means of a pair of spade terminal clips 15 and 16 which are enclosed by an insulated cable covering 17.

The telephone line is coupled to the recorder amplifier through the spade terminal clips 15, 16 by means of a pair of conductors 18, 19 (see Fig. 2), forming part of a closed circuit including a pair of high resistors 20, 21 (which may be of the order of 1,000 ohms), a pair of condensers 22, 23 (which may be of the order of 1 microfarad) and which serve to thoroughly isolate the telephone line from the automatic volume control unit and the recording apparatus. The condensers 22, 23 are joined by conductors 24, 25 to the primary coil 26 of a transformer 27 having a secondary coil 28.

Connected to the secondary coil 28 of the transformer 27 are a pair of conductors 29, 30, the former having a high resistance 31 (of the order of 1250 ohms) in series therewith and which leads through a wire 32 to a variable resistance 33. An arm 34 manually controlled by a pointer knob 35 (Fig. 1) is in electrical contact with said resistance 33 and leads to one "telephone" terminal 36 of a double-throw double-pole switch arm 37 which serves for selectively connecting the telephone line with a pair of central switch terminals 38, 39 leading through wires 40, 41 to the outer terminals 42, 43 of a four-prong plug for insertion into a socket (not shown) on the recorder amplifier.

The conductor 30 is connected to a cross wire 44 having a condenser 45 (about 80 microfarads) located therein, which in turn leads through conductors 46, 47 to the other "telephone" terminal 48 of the switch 37. The arm 34 is connected to the conductor 47 by a conductor 48a which includes a resistance 48b.

The switch 37, when swung to the opposite position from that shown on the drawings, is adapted to engage a pair of terminals 49, 50 which

are connected by lead wires 51, 52 to the outer terminals of a four-prong microphone socket 53 connected by a cable 54 to a microphone 55 for use when a recording is to be made of a conference or ordinary dictation.

The two central terminals 56, 57 of the amplifier are joined by wires 58, 59, and 60, 61 to the central terminals 62, 63 respectively of the four-prong microphone socket. Provision is also made of a conductor wire 64 leading from the junction of wires 58, 59 to the core 65 of the transformer, said core being connected to an electrostatic shield in the transformer between the primary and secondary windings.

15 The present automatic volume control unit is provided with a pair of copper oxide rectifiers 66, 67, the former of which is connected in shunt with the transformer secondary 28 by means of a wire 68 and a wire 69 leading to the junction 70 between the conductors 46, 47.

The second rectifier 67 is connected to a two-prong plug 71 leading from the output of the recorder amplifier through a pair of conductors 72, 73 (as shown in Figure 2). The wire 72 leads by a wire 74 to the junction 70, while the wire 73 leads through a small resistance 75 (25 ohms) to a wire 76 joined to one side of the rectifier 67.

The other side of said rectifier 67 is joined by a wire 77 and a resistance 78 (about 200 ohms) to the wire 30.

30 In order to filter the amplifier output as well as to rectify it, provision is made of a second condenser 79 (about 80 microfarads) which cooperates with the resistance 75, the resistance 78, 35 the condenser 45 and a resistance 80, the latter being joined to the wires 74 and 77 as shown in Figure 2. If desired an additional condenser 81 may be connected to the wires 74 and 77 between the resistance 80 and the rectifier 67 in cases 40 where there are an excessive amount of high frequency signals passing through the amplifier, and which tend to exert an inordinate control over the circuit.

Operation

45 In operation, the condenser 81 serves to eliminate the effect of such high frequency signals and limits the volume control action to the lower frequency signals which occur in ordinary voice recording. This insures that the automatic volume control will be operative only on the lower frequency speech signals and that the high pitch portion of the energy will take no part in said control. The automatic volume control unit of the present invention may be fastened to the back of a standard recorder cabinet by means of screws 82, as shown in Figure 1. The spade terminals 15, 16 will then be attached to suitable terminals on the telephone equipment. After adjusting the control knobs 12 and 35, the apparatus will be ready for use.

50 It will be understood that by connecting the copper oxide rectifier 67 to the output of the recorder amplifier for rectifying a portion of said output and filtering it through a network of "smoothing" condensers and a resistor, a D.C. bias will be provided free from signal ripples. A time delay will also be introduced which may be varied by changing the series resistances or the filter condenser capacity. The control of this time delay is necessary to avoid distortion and "choppiness" which would result from an instantaneous action, or too rapid an action between syllables of a word. Moreover, too slow an action

will cause loss of the first parts of a weak voice following a strong one.

It will be understood that the amount of bias of the second rectifier 67 changes with the output signals and this in turn changes the impedance of the shunting rectifier unit.

Modified form

In the modified form of the invention illustrated in Figure 3, a pair of shunting rectifiers 83, 84 arranged in "push-pull" relation are employed in place of the simple shunting rectifier 66, shown in Figure 2.

The rectifiers 83, 84 serve to balance out any unrectified signals which have passed through the filter system. By the use of this push-pull arrangement, much less filtering is necessary, or in other words, the condensers may be made of smaller capacity. A further advantage due to the elimination of the unrectified signals lies in the fact that regenerative effects are entirely avoided.

The rectifiers 83, 84 are connected to the conductors 31, 30 by wires 85, 86 respectively, and are connected together by an intermediate conductor 87, the latter being joined at its midpoint 88 to a conductor 89 leading to the conductor 74. In this form of the invention, the secondary 28 is tapped at its midpoint 80 and connected to the conductor 71 by a conductor 91. The condenser 45 in this instance is connected to the conductors 89 and 91, instead of to the conductors 14 and 77 as in the first form of the invention.

In the modified form of hookup shown in Figure 4, the telephone line is applied to a vacuum tube "preamplifier" 92, whose output is connected by conductors 93, 94 to a pair of resistors 95, 96 constituting a voltage divider. A rectifier 97 is in a shunt circuit including the resistor 96. The condenser 45 is of high capacity and acts for all practical purposes like a solid connection for A. C. between the junctions 98 and 99. In this form of the invention, the biasing rectifier 67, the condensers 45, 78, and 81 and the resistances 75 and 80 all perform the same functions as in the first two forms of the invention.

One advantage of the modified form shown in Figure 4 is that the rectifier 97 acts as a low resistance shunt for strong signals across the resistor 96. It also permits a larger range of volume control due to the preamplifier, and reduces the level of undesired amplifier noises arising from sources other than the voice or other sounds to be recorded.

An important feature of the present invention lies in the fact that the improved volume control apparatus is used with a circuit which has inherently a tremendous amount of attenuation. In other words, in order to function within the range required, a considerable amount of loss has to be introduced in order to adapt the telephone line voltages to the voltages permissible for the operation of the recorder amplifier.

One advantage of the present invention is that it provides a highly convenient unit for attachment to a recorder amplifier without requiring any changes to be made in the amplifier circuit and without the necessity of the use of vacuum tubes, batteries, or other energy consuming devices.

While there have been disclosed in this specification several forms in which the invention may

be embodied, it is to be understood that these forms are shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new and for which it is desired to secure Letters Patent is:

1. In a gain control system, a high resistance primary circuit connected to the terminals of a telephone line, a secondary circuit transformer coupled to said primary circuit, means to connect said secondary circuit to the input of a recorder amplifier, a copper oxide rectifier shunted across said secondary circuit, and a second copper oxide rectifier energized by a portion of the output from said amplifier to vary the load of said shunting rectifier in accordance with the strength of the signals in said telephone line.

2. In a system for recording telephone conversations from local and distant points, a high resistance primary circuit connected to the terminals of a telephone line, a secondary circuit coupled to said primary circuit and having a variable resistance therein, a recorder amplifier, a switch for connecting said secondary circuit to the input of said amplifier, a rectifier shunted across said secondary circuit, and means for impressing a portion of the output from said amplifier upon said rectifier to cause the impedance of said rectifier to vary inversely with the input energy and thus maintain a uniform amplifier gain.

3. In a system for selectively recording telephone conversations and signals received from a microphone, a high resistance primary circuit connected to the terminals of a telephone line, a secondary circuit coupled to said primary circuit, a microphone circuit, a recorder amplifier circuit, and means for selectively connecting said secondary circuit and said microphone circuit to said amplifier circuit, said secondary circuit having a copper oxide gain control rectifier in shunt therewith.

4. In a system for recording telephone conversations from local and distant points, a pre-amplifier connected to the terminals of a telephone line, a high resistance circuit connected with said pre-amplifier and including a rectifier in shunt therewith, a recorder amplifier, and means for filtering and impressing a portion of the output from said recorder amplifier upon said secondary circuit to vary the shunting load of said rectifier in accordance with the strength of the applied energy whereby a uniform volume of amplification will be produced and recorded.

5. In a system for recording telephone conversations from local and distant points, a high resistance primary circuit connected to the terminals of a telephone line, a secondary circuit coupled to said primary circuit, a pair of rectifiers in push-pull arrangement shunted across said secondary circuit, a recording amplifier connected to said secondary circuit, and means for impressing a portion of the output from said amplifier upon said secondary circuit to vary the impedance of said rectifier inversely in accordance with the input energy and thus maintain a uniform amplifier gain.

LINCOLN THOMPSON.
